UNITED STATES PATENT OFFICE.

FRED A. PUTNAM, OF MELROSE, MASSACHUSETTS, ASSIGNOR TO SEWING MACHINE SUPPLIES COMPANY, OF BOSTON, MASSACHUSETTS, A CORPORATION OF MASSACHUSETTS.

TAG-HOLDER FOR SHOE-RACKS.

No. 909,219.

Specification of Letters Patent.

Patented Jan. 12, 1909.

Application filed February 17, 1908. Serial No. 416,191.

To all whom it may concern:

Be it known that I, FRED A. PUTNAM, a citizen of the United States, residing at Melrose, county of Middlesex, and State of Massachusetts, have invented an Improvement in Tag-Holders for Shoe-Racks, of which the following description, in connection with the accompanying drawing, is a specification, like letters on the drawing representing like parts.

This invention has for its object to provide a novel tag-holder for shoe-racks.

It is now the common practice in the manufacture of shoes to carry the shoes through the various steps of manufacture in separate lots, each lot being placed on a shoe-rack by which it is transported from one part of the factory to the other for the various operations in making a shoe, such as lasting, sole leveling, stitching, etc. It often happens that the lot of shoes on some particular rack requires some special instructions concerning their manufacture, and it is now the common practice to place upon a rack containing a lot of shoes which thus need special instructions a tag containing such instructions.

It is the object of my invention to provide a novel tag-holder which can be quickly secured to or removed from the rack and which will be held firmly in its position when applied to the rack.

Referring now to the drawings wherein I have shown one embodiment of my invention, Figure 1 is a perspective view of a shoe-rack to which my improved tag-holder is to be applied; Fig. 2 is a side view on an enlarged scale of the tag-holder; Fig. 3 is a section on the line $x-x$, Fig. 2; Fig. 4 is a top plan view of the tag-holder support.

3 designates a shoe-rack which may be of any suitable or usual construction and to which my improved tag-holder is to be applied.

45 My improved tag-holder is made from a piece of wire and is shaped to form the resilient stem 4 having the clip portion 5 at the upper end thereof and the laterally-extended arm 7 at the lower end thereof. The 50 clip portion can be conveniently formed by bending the end of the wire into a coil, as shown in Figs. 2 and 3, between the turns of which the tag or label 6 may be inserted.

The stem 4 is supported by the rack by means of a supporting member 8 which is

adapted to be permanently secured to the rack. This supporting member may be made of sheet metal and is formed at its lower end with the eye or hinge portion 9 into which the laterally-bent arm 7 may be inserted, and it is also formed at its upper end with the catch 10 which is adapted to engage the stem and hold it in proper position. This catch 10 may conveniently be formed by bending the upper edge of the sheet metal supporting member 8 to form the flange 11, and then shaping said flange to form the catch. The catch stands substantially in line with one end of the hinge portion 9, as best seen in Fig. 2.

The supporting member 8 is intended to be firmly secured to the rack and whenever it is desired to apply a tag or label to the rack, the operator takes a wire holder 4 and inserts the arm 7 into the eye 9 while the stem is in the dotted line position Fig. 3, and then said stem is swung into the vertical position shown in full lines Fig. 3. In moving into the vertical position, the stem snaps in behind the catch 10 and the resiliency of the stem holds it firmly behind the catch. The tag or label 6 with the proper directions thereon is then inserted in the coil 5. To remove the tag-holder it is simply necessary to swing the stem 4 to the left, Fig. 2, sufficiently to disconnect said stem from the catch 10 when said stem may be swung into the dotted line position Fig. 3 and then removed laterally from the eye 9.

My tag-holder is very simple to make and 90 may be quickly applied to or removed from the rack.

Having fully described my invention, what I claim as new and desire to secure by Letters Patent is:—

1. The combination with a shoe-rack, of a supporting member secured thereto, said supporting member being provided with a catch, and a tag-holder presenting a resilient stem hinged to the supporting member 100 but removable therefrom and adapted to be engaged by the catch when it is in operative position, said tag-holder presenting at its upper end a tag-receiving clip.

2. The combination with a shoe-rack, of a supporting member secured thereto and provided with a catch and a hinge member, a tag-holder presenting a resilient stem having a laterally-extending arm at one end adapted to be inserted into the hinge mem- 110

ber, and a tag-holding clip at the other end, said catch being positioned to engage the stem of the tag-holder when the latter lies against the supporting member thereby to maintain said tag-holder in vertical position.

3. A tag-holder for shoe-racks comprising a supporting member made of sheet metal and having one edge curled up to form a hinge member and the opposite end 16 bent to form a lateral flange provided with a catch, and a wire member presenting a resilient stem having at one end a tag-holding

clip and at the other end a laterally-extending arm to be received in the hinge member, said catch being positioned to engage the 15 stem and hold the latter against the body of the supporting member.

In testimony whereof, I have signed my name to this specification, in the presence of two subscribing witnesses.

FRED A. PUTNAM.
